UNITED STATES PATENT OFFICE.

ANDREAS RALOVANOVIC, OF ZURICH, SWITZERLAND.

TWO-STROKE CYCLE-MOTOR.

1,068,168.

Specification of Letters Patent.

Patented July 22, 1913.

Application filed February 11, 1910. Serial No. 543,392.

To all whom it may concern:

Be it known that I, ANDREAS RALOVANOVIC, a citizen of the Republic of Switzerland, residing at Zurich, in Switzerland, have invented certain new and useful Improvements in Two-Stroke Cycle-Motors; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has for its object a two-stroke cycle motor, in which the distributing means are arranged, instead of on the working cylinder itself, on the cover of the same, and in which the supply of the mixture of air and gas is effected through channels provided in the piston rod.

In the drawings—Figures 1 to 5 show by way of example a form of execution of the invention with piston valves, and Figs. 6 to 10 another form with rotary grid valves. Fig. 1 is a vertical longitudinal section of the motor. Fig. 2 a side elevation thereof. Fig. 3 a front elevation partly in section seen in the direction of arrow *x* in Fig. 1. Fig. 4 is a vertical section taken on line C—D of Fig. 1 and seen in the direction of arrow *x*. Fig. 5 is a vertical section on line A—B of Fig. 1, seen in the same direction. Fig. 6 is a front elevation, partly in section, of a modified form of the invention, with rotary grid-valves. Fig. 7 is a partial vertical section of the distributing means of the modification. Fig. 8 is a cross section taken on planes corresponding to the planes of section designated by lines A—B and C—D in Fig. 1. Fig. 9 is a vertical section of a somewhat modified form of execution, wherein a tubular valve is employed instead of a piston valve, and Fig. 10 is a vertical section of a modified form of execution of the rotary grid-valves.

Fig. 1 shows a double-acting two-stroke cycle motor just in the moment when the piston *k*, is in its rear dead center position in the cylinder *z*. In the middle of the cylinder and on its circumference are provided slots or openings *u* which the piston *k* will clear before the same has attained its dead center position and which serve as outlets for the burned gases.

For the admission of gas and air into the cylinder *a*, channels or grooves *v* are provided in the piston rod *k* by means of which the cylinder space may be put in communication with the gas and air chambers *g* and *l* respectively.

The distribution is effected by two piston-valves *s* and *s'* for the air and gas respectively, both arranged concentrically around the piston rod.

The piston-valve *s'* consists of two parts connected by the webs *s*² and between which a free space *b* is left forming a chamber 70 around the piston rod. By means of this chamber *b*, the cylinder *a* may be put into communication with the air chamber *l* when the grooves *v* are in the position shown in Fig. 1. The movement of the distributing 75 valves *s* and *s'* can be effected by any suitable valve gear, as for instance by the cam gear shown in Figs. 2 and 3. The shaft *w* (Fig. 3) actuated from a crank (not shown) drives by means of suitable gearing *y*, *y*₁ 80 a shaft *w*₁, on which latter two cam disks *d* and *d'* are arranged. These cam disks engage rollers *r* and *r*₁ carried by the levers *h* and *h'* mounted on pivots *o*, *o'* respectively and cause an axial displacement of 85 the distributing valves *s* and *s'*, to which said levers are connected by rings *q*, *q'*. The gas and the air are brought to the desired degree of pressure in the chambers *g* and *l* respectively by means of one or 90 several pumps (not shown).

Instead of the piston-valves above described, rotary grid-valves such as shown in Figs. 6, 7 and 8, may be arranged, in which case these latter will be actuated by 95 means of cam-disks *d*² and *d*³ (Fig. 6), which are mounted directly on shaft *w* and engage rollers *r*² and *r*³, carried by bell-crank levers *m* and *m*₁ which actuate rods *n* and *n'* and levers *h*² and *h*³ which are 100 connected to and move rotary grid-valves *s*³ and *s*⁴. Instead of providing grooves or channels *v* in the piston rod *k*, a sleeve *f* (Figs. 7 and 8) provided with slots may be put around the smooth piston rod *k*, in 105 which case the passage for the air and gas is formed by the space *v'* between the sleeve and piston rod.

Fig. 9 shows a modified form in which tubular valves, as *S*⁵, *S*⁶, are used instead of the piston valves and Fig. 10 shows a modification of the rotary valves, as *S*⁷, *S*⁸, having conical packing surfaces.

The manner of working the motor is as

follows: Before attaining its dead center position at about $\frac{1}{3}$ to $\frac{1}{2}$ of its stroke the piston clears the openings or slots *u* and the exhaust of the burned gases begins. Immediately afterward the space *a* of the cylinder is connected with the air admission chamber *b* by the grooves *V*, or spaces *V'*. Independently of the movement of the piston itself the air valve is moved by its cam-disk so as to admit the compressed air to the cylinder, whereupon the air will completely drive out the burned gases. During the admission of air into the cylinder, the gas valve is opened to admit the required quantity of gas and is then closed whereupon the air will drive the gas into the cylinder that has entered the grooves *V* or spaces *V'*. In order to open the air valve before the gas valve, to drive out the burnt gases, and to hold said air valve open during the time the gas valve is open, so that the gas admitted to the grooves or spaces will be driven into the cylinder, the cam-disk which operates the air valve is longer than the cam-disk which operates the gas-valve. During the period of opening and closing of the valves, the piston has begun its backward stroke and has once more shut the grooves whereupon the compression begins in the ordinary way and the complete operation is carried out in the usual manner.

I claim—

1. A two-stroke cycle motor comprising a cylinder, a piston therein, gas and air chambers separate from each other and surrounding the piston rod, said rod formed with passages to establish communication between said chambers and the cylinder.

2. A two-stroke cycle motor comprising a cylinder, a piston therein, gas and air chambers, separate from each other and surrounding the piston rod formed with passages to establish communication between said chambers and the cylinder, the said passages being opened and closed alternately by the movement of the piston rod.

3. A two-stroke cycle motor comprising a cylinder, a piston therein, gas and air chambers separate from each other and surrounding the piston rod, said rod formed with passages to establish communication between said chambers and the cylinder and means to govern the admission of air and gas to said passages.

4. A two-stroke cycle motor comprising a cylinder, a piston therein, gas and air chambers separate from each other and surrounding the piston rod, said rod formed with passages to establish communication between said chambers and the cylinder and an admission chamber interposed between one of said chambers and the passages.

5. A two-stroke cycle motor comprising a cylinder, a piston therein, gas and air chambers separate from each other and surround-

ing the piston rod, said rod formed with passages to establish communication between said chambers and the cylinder, means to govern the admission of air and gas to said passages and an admission chamber interposed between one of said chambers and the passages.

6. A two-stroke cycle motor comprising a cylinder, a piston therein, gas and air chambers separate from each other and surrounding the piston rod, said rod formed with passages to establish communication between said chambers and the cylinder, said passages being opened and closed alternately by the movement of the rod, means to govern the admission of air and gas to said passages and an admission chamber interposed between one of said chambers and the passages.

7. A two-stroke cycle motor comprising a cylinder, a piston therein, gas and air chambers separate from each other and surrounding the piston rod, said rod formed with passages to establish communication between said chambers and the cylinder and valves to control the admission of air and gas to said passages.

8. A two-stroke cycle motor comprising a cylinder, a piston therein, gas and air chambers separate from each other and surrounding the piston rod, said rod formed with passages to establish communication between said chambers and the cylinder, valves to control the admission of air and gas to said passages and an admission chamber interposed between one of said chambers and the passages.

9. A two-stroke cycle motor comprising a cylinder, a piston therein, gas and air chambers separate from each other and surrounding the piston rod, said rod formed with passages to establish communication between said chambers and the cylinder, a valve to control the admission of gas to the passages and admission chamber interposed between the air chamber and the passages and a second valve to control the admission of air to the admission chamber.

10. A two stroke cycle motor comprising a cylinder, a piston therein, gas and air chambers separate from each other and surrounding the piston rod, said rod formed with passages to establish communication between the chambers and the cylinder, said passages being opened and closed alternately by the movement of the rod, a valve surrounding the piston rod to control the admission of gas to the passages, an admission chamber formed in said valve, interposed between the air chamber and the passages and a second valve surrounding the first, to control the admission of air to the admission chamber.

11. A two-stroke cycle motor comprising a cylinder, a piston therein, gas and air

- chambers separate from each other and surrounding the piston rod, said rod formed with passages to establish communication between the chambers and the cylinder, said 5 passages being opened and closed alternately by the movement of the rod, a valve surrounding the piston rod and working thereon to control the admission of gas to the passages, an admission chamber formed 10 in said valve being formed so as to maintain communication between the air chamber and the passages during the working of the valve, a second valve surrounding the first, to control the admission of air to the 15 passages through the admission chamber, this admission of air being rendered independent of the gas admission by the interposition of the admission chamber.
12. In a two-stroke cycle motor a cylinder having exhaust ports, a piston working therein, gas and air chambers separate from each other, a piston rod formed with 20 passages to establish communication between said chambers and the cylinder, and rotary valves governing the admission of 25 air and gas to said passages.
13. In a two-stroke cycle motor a cylinder having exhaust ports, a piston working therein, alternately opening and closing the 30 ports by its movement, gas and air chambers, a piston rod formed with passages set into communication with the cylinder by the movements of the rod, a rotary valve 35 surrounding the piston rod governing the admission of gas to said passages and a second rotary valve surrounding the rod to govern the admission of air to said 40 passages.
14. In a two-stroke cycle motor, a cylinder having exhaust ports, a piston working therein, alternately closing and opening the exhaust ports by its movement, gas and air chambers, a piston rod formed with 45 passages set into communication with the cylinder by the movement of the rod, a rotary valve surrounding the rod, to govern the admission of gas to said passages, an admission chamber formed in said rotary valve by dividing it into separate parts 50 connected with webs and interposed between the air chamber and the passages and a second rotary valve surrounding the first to govern the admission of air to the admission chamber.
- 55 15. In a two-stroke cycle motor a cylinder having exhaust ports, a piston working therein, alternately closing and opening said ports by its movement, gas and air chambers surrounding the piston rod, said 60 rod being formed with passages set into communication with the cylinder by the movements of the rod, a rotary valve surrounding the rod governing the admission of gas to the passages, an admission chamber formed in said rotary valve, a second 65 rotary valve surrounding the rod governing the admission of air to the passages through the admission chamber, means to actuate said valves independently of each other, the admission chamber rendering the 70 air admission independent of the gas admission.
16. In a two-stroke cycle motor, a cylinder having exhaust ports, a piston working therein, alternately closing and opening 75 said ports by its movement, gas and air chambers, surrounding the piston rod, said piston rod being formed with passages set into communication with the cylinder by the movements of the rod, a rotary valve 80 surrounding the piston rod and governing the admission of gas to the passages, an admission chamber formed in said valve by dividing it into separate parts connected by webs, a second rotary valve surrounding the 85 first rotary valve and governing the admission of air to the passages through the admission chamber, independently from the gas admission and means operated independently of the piston rod to actuate said 90 valves.
17. In a two-stroke cycle motor, a cylinder having exhaust ports, a piston working alternately closing and opening 95 said ports by its movement, gas and air chambers, surrounding the piston rod, said rod being formed with passages set into communication with the cylinder by the movement of the rod, a rotary grid valve 100 concentric to the rod and working thereon, governing the admission of air to said passages, an admission chamber formed in said valve by dividing it into separate parts 105 connected by webs, communicating directly with said passages, means independent of the movement of the rod to actuate said valve, a second rotary grid valve arranged concentrically to the first and working thereon, governing the admission of air to the 110 passages through the admission chamber independently of the gas admission and means independent of the first-named means to actuate the rotary grid valve for the air admission.
- In testimony that I claim the foregoing 115 as my invention, I have signed my name in presence of two subscribing witnesses.
